UNITED STATES PATENT OFFICE

FRANKLIN M. DANIELS, OF SALINA, KANSAS

VALVE TOOL

Application filed December 20, 1928. Serial No. 327,380.

The present invention relates to valve tools and an important object thereof is to provide a valve tool which will effectively remove the inner valve stem from the valve casing 5 when the lugs on the valve plug about the stem have become broken off.

Another very important object of the invention resides in the provision of a tool of this nature which is exceedingly simple in 10 its construction, inexpensive to manufacture, strong and durable, easy to manipulate, thoroughly efficient and reliable in use and operation and otherwise well adapted to the purpose for which it is designed.

15) With the above and numerous other objects in view as will appear as the description proceeds, the invention resides in certain novel features of construction, and in the combination and arrangement of parts as will be hereinafter more fully described and claimed.

In the drawing:

Figure 1 is a fragmentary elevation of a wheel showing my tool associated with the valve of the tire thereon,

25) Figure 2 is a perspective view of the head of the tool,

Figure 3 is an enlarged detail section taken substantially on the line 3—3 of Figure 1,

30) Figure 4 is a longitudinal section through the tool,

Figure 5 is a perspective view of the shank, and

Figure 6 is a sectional view taken substantially on the line 6—6 of Figure 4.

35) Referring to the drawing in detail, it will be seen that the numeral 5 denotes a valve casing with the usual plug 6 threaded therein through which valve stem 7 usually extends as will be appreciated by those skilled in this art.

When the lugs on the plug 6 become broken off, of course, it is very difficult to remove this plug in order to remove the "valve insides".

40) The letter H denotes generally a handle of oblong construction tapering toward one end. This handle is provided with an elongated slot 8 and the smaller end thereof is provided with a threaded opening 9 for threadedly receiving a shank 10 which is threaded as at 11 for this purpose.

The larger end of the handle has swivelly mounted thereon a head 12 which is shaped to fit in the crotch between two spokes of a wheel as is clearly illustrated in Figure 1. This head has a neck 14 rotatable in opening 15 which is enlarged intermediate its ends to form a shoulder 16 and a flange 17 on the neck portion and engages this shoulder to hold the head adjacent the plate.

The shank 10 terminates in a pointed end 19 which is non-circular in cross section, preferably square as indicated to advantage in Figure 6 so as to form edges 20. An intermediate portion of the shank is enlarged and threaded as indicated at 21 so that a thumb nut 22 may be engaged thereon.

When it is desired to remove the "valve inside" stem 7 is forced through the plug 6 and the pointed end 19 is placed in the opening of the plug and the head 12 in the crotch between the adjacent spokes of the wheel and then by turning the handle 8 the point 19 is forced into the plug until the edges 20 bite into the opening at which time it will be seen that the shank 10 may be turned by the thumb nut 22, to unthread the plug 6 from the casing 5 thereby permitting easy removal of the "valve insides".

It will be seen that the tool is exceedingly simple in its construction and may be manipulated with great ease eliminating the necessity of taking the tire off the wheel and removing the inner tube from the tire.

The present embodiment of the invention, however, has been described merely for the purpose of exemplification since in actual practice it attains the features of advantage enumerated as desirable in the statement of the invention and the above description.

It will be apparent that changes in the details of construction, and in the combination and arrangement of parts may be resorted to without departing from the spirit or scope of the invention as hereinafter claimed or sacrificing any of its advantages.

Having thus described my invention, what I claim as new is:

1. A valve tool of the class described, comprising a handle adapted for disposition within the spokes of a wheel, a shank having

one end threaded into the handle, and the other end of said shank being of non-circular cross section forming edges to grip a valve plug, said other end of the shank merging into a point to admit the same within the opening of the valve plug, heads swivelly mounted upon the handle at the end remote from the shank and adapted to be received in the adjacent spokes, and a wing nut 10 threadedly engaged on the shank adjacent the pointed end, whereby the shank may be rotated to unthread the plug from the valve casing.

2. A valve tool of the class described comprising a handle adapted for disposition between the spokes of the vehicle wheel, a shank having one end threaded into the handle, said shank having its other end substantially square in cross section to form plug 20 engaging edges, the said other end of the shank merging into a point to admit the same within a valve casing for frictional engagement with the plug of a valve, a head swivelly mounted on the handle at the end remote from the shank and adapted to be received in adjacent wheel spokes, and said shank adapted to be rotated independently of the handle for unthreading a plug from the valve casing.

30 In testimony whereof I affix my signature.
FRANKLIN M. DANIELS.
